UNITED STATES PATENT OFFICE.

JOHN W. ROBERTS, OF SARNIA, ONTARIO, CANADA.

PIPE-CO尤PLING FOR RAILWAY ROLLING-STOCK.

1,324,270.

Specification of Letters Patent.

Patented Dec. 9, 1919.

Application filed December 3, 1918. Serial No. 265,110.

To all whom it may concern:

Be it known that I, JOHN W. ROBERTS, of the city of Sarnia, in the county of Lambton, Province of Ontario, Canada, have invented 5 certain new and useful Improvements in Pipe-Couplings for Railway Rolling-Stock, of which the following is a specification.

This invention relates to means for automatically coupling together the air and 10 steam pipes of railway rolling stock such as shown and described in my prior United States Patent No. 1,121,763 of December 22nd, 1914, and my object is to improve my prior construction in certain details.

15 It has been found in practice desirable to provide means for better holding the forward ends of the coupling members against relative vertical or lateral displacement without interfering in any way with their 20 independent longitudinal movement; to provide improved means for holding the supporting frames for the coupling members of two coöperating couplings in exact alignment; and to provide improved means for 25 guiding the coupling members on their supporting frame and for limiting their extension.

I attain my object by means of the constructions hereinafter described and illustrated in the accompanying drawings in which—

Figure 1 is a side elevation showing two couplings in their coupled position;

Fig. 2 a front elevation of a coupling;

35 Fig. 3 a section through one of the couplings on the line *a—a* in Fig. 1; and

Fig. 4 a perspective detail of parts of the divided head showing their interengaging ribs.

40 In the drawings like numerals of reference indicate corresponding parts in the different figures.

1 is a frame provided with top and bottom members 2 and 3. In the rear end of 45 this frame is journaled the vertical bar 4 provided with horizontally extending trunnions 5. By means of these trunnions the device will be suspended, though such connections form no part of the present invention 50 and are neither shown nor described.

The forward ends of the top and bottom members 2 and 3 are held together by means of the bail 22, the ends of which are connected with trunnions 23 formed on the bottom member 3. The bail is preferably divided 55 at its upper end, and the ends con-

nected by a bolt 24. The top member is provided with ribs 25 between which the upper end of the bail 22 is fitted.

The frame supports the coupling members 6. These are usually three in number and are superimposed on one another so that each may slide longitudinally of the frame independent of the others. It is necessary that each coupling member should be yieldingly extended so that it may be maintained by spring pressure in contact with a corresponding coupling member of an opposed coupling. For this purpose I provide the 60 springs 7, each of which engages the rear end 65 of the frame and a boss 8 on the corresponding coupling member.

It is necessary to limit the degree of extension of the coupling as a whole and also to limit the amount of independent movement of each coupling member. It will be noted that the rear ends of the coupling members are provided with bosses 9 adapted to slide on one another and to properly space the coupling members. The outer 70 coupling members are also provided with the projections 10 which enter slots 11 in the top and bottom members 2 and 3 of the frame. These projections by contacting with the forward ends of the slots limit the 75 extension of the outer coupling members. The extension of the intermediate member is limited by a yoke 12 secured to the frame and embracing one of the bosses 9 of the intermediate coupling member. 80

To maintain the coupling members in alignment, I prefer to form in certain of the bosses 9 a longitudinal groove 13 which may engage a rib 14 formed on the adjacent boss. Only one of these ribs and grooves is 85 shown in Fig. 1 of the drawings, but it will be understood they are preferably employed between each pair of contacting bosses. 90

Farther forward the upper and lower coupling members are provided with ribs 26 which fit between lugs 27 formed on the top 100 and bottom members of the frame so as to serve as guides for the longitudinal ribs 26. The upper and lower coupling members are thus restricted to fore and aft sliding movement longitudinally of the frame, while the intermediate coupling member, owing to the constructions hereinafter described, is held at its forward end from shifting laterally relative to the outer coupling member. 105

As in the prior patent hereinbefore referred to, the outer ends of the coupling 110

members are shaped to form a head divided horizontally, and around the bore of each coupling member where it opens through the head is fitted a washer or gasket 15 having 5 a flat outer face which engages with the flat outer face of the gasket of the opposed coupling member.

To guide the opposing coupling members into proper engagement, I provide each 10 member with the outwardly curved guards 16, one being connected to one side of one of the outer parts of the head and the other to the other side of the other outer part of the head.

15 To interlock the parts 17 of the head against relative vertical displacement, I extend up the inner end of each guard to overlap the side of the intermediate part of the head and provide the inner end of the 20 guard with a rib 18. A groove 19 is formed in the side of the head so as to form a shoulder engaging with the under side of the rib 18. Thus each outer part 17 of the head is locked to the intermediate portion of the head to resist vertical displacement. Preferably also the ribs engage the bottoms of the grooves 19 to hold the parts of the head against horizontal displacement. The ribs 18 are preferably made sufficiently long and 30 the grooves 19 sufficiently wide for engagement with the grooves and ribs of a similar head of an opposed coupling. This interlocking serves to maintain proper alignment of the opposed coupling members.

35 I have also found it desirable to provide means for rigidly maintaining the alignment of the opposed coupling frames. I therefore provide the lower member 3 of the frame with a projecting tongue 20 and parallel therewith a socket member 21, which socket member is preferably open on its under side and is adapted to receive the tongue 20 of the opposed coöperating coupling.

40 From the above description it will be seen that when the two coupling heads are interlocked as shown in Fig. 1, it is impossible for the coupling frames to get out of alignment relative to the vertical plane passing through them. The coupling heads also will 45 be held in perfect alignment and yet the independent longitudinal movement of each individual coupling member has in no wise been interfered with.

45 What I claim as my invention is:—

50 1. In an automatic pipe coupling for railway rolling stock, the combination of a frame; a plurality of superimposed coupling members supported to move longitudinally of said frame either unitedly or independently; springs tending to extend said members; means for limiting the extension of said members as a whole, the forward ends of the coupling members being shaped to form a head, divided horizontally and 55 adapted to interlock with the similar head of

an opposed coupling; and co-acting longitudinal rib-and-groove connections between the parts of said head at each side preventing the relative displacement of the coupling members except in a longitudinal direction. 70

2. In an automatic pipe coupling for railway rolling stock, the combination of a frame; a plurality of superimposed coupling members supported to move longitudinally of said frame either unitedly or independently; springs tending to extend said members; means for limiting the extension of said members as a whole, the forward ends of the coupling members being shaped to form a head, divided longitudinally and 75 adapted to interlock with the similar head of an opposed coupling; and parts on said divided head at each side overlapping and interlocking to prevent vertical displacement of the coupling members. 80

3. In an automatic pipe coupling for railway rolling stock, the combination of a frame; three superimposed coupling members supported to move longitudinally of said frame either unitedly or independently; springs tending to extend said members; means for limiting the extension of said members as a whole, the forward ends of the coupling members being shaped to form a head divided horizontally and adapted to 85 interlock with the similar head of an opposed coupling; and a member at one side of one outer part of the head and at the other side of the other part of the head 90 overlapping the sides of the intermediate part, said members and the intermediate part of the head being formed with co-acting 95 longitudinal shoulders adapted to prevent vertical relative displacement of the coupling members. 100

4. In an automatic pipe coupling for railway rolling stock, the combination of a frame; three superimposed coupling members supported to move longitudinally of said frame either unitedly or independently; 110 springs tending to extend said members; means for limiting the extension of said members as a whole, the forward ends of the coupling members being shaped to form a head divided horizontally and adapted to 115 interlock with the similar head of an opposed coupling; a guard at one side of one outer part of the head; a guard at the other side of the other outer part of the head, the inner ends of said guards overlapping the 120 sides of the intermediate part of the head; and an inwardly projecting longitudinal rib formed on each guard, the intermediate part of the head being grooved to receive 125 said ribs. 125

5. In an automatic pipe coupling for railway rolling stock, the combination of a frame; three superimposed coupling members supported to move longitudinally of said frame either unitedly or independ- 130

ently; springs tending to extend said members; means for limiting the extension of said members as a whole, the forward ends of the coupling members being shaped to form a head divided horizontally and adapted to interlock with the similar head of an opposed coupling; a guard at one side of one outer part of the head; a guard at the other side of the other outer part of the head, the inner ends of said guards overlapping the sides of the intermediate part of the head; and an inwardly projecting longitudinal rib formed on each guard, the intermediate part of the head being grooved to receive said ribs, said ribs being long enough and said grooves wide enough for engagement with the grooves and ribs of a similar head of an opposed coupling.

6. In an automatic pipe coupling for rail-way rolling stock, the combination of a frame having longitudinally slotted top and bottom members; a plurality of superimposed coupling members supported thereon

and independently slideable relative to one another; a boss on each outer member slideable in the slots of the frame; a longitudinal rib on each outer member forward of the boss; and lugs on the top and bottom members of the frame forming guides for the ribs.

7. In an automatic pipe coupling for rail-way rolling stock comprising a frame and coupling members carried thereby, means for maintaining the frames of two opposed coöperating couplings in alinement comprising a horizontal tongue projecting longitudinally from the forward end of the frame and a socket member parallel thereto adapted to receive the tongue of the frame of an opposed coupling.

Signed at Sarnia, Ontario, Canada, this 22nd day of November, 1918.

JOHN W. ROBERTS.
